UNITED STATES PATENT OFFICE.

HOMER H. DUNLAP, OF OKLAHOMA, OKLAHOMA, ASSIGNOR TO WESTERN MFG. CO., OF OKLAHOMA, OKLAHOMA, A CORPORATION OF OKLAHOMA.

FLASHING.

1,201,947.

Specification of Letters Patent. Patented Oct. 17, 1916.

Application filed March 20, 1916. Serial No. 85,474.

To all whom it may concern:

Be it known that I, HOMER H. DUNLAP, a citizen of the United States, residing at Oklahoma, in the county of Oklahoma and 5 State of Oklahoma, have invented certain new and useful Improvements in Flashings; and I do declare the following to be a full, clear, and exact description of the invention, such as will enable others skilled in the art 10 to which it appertains to make and use the same.

My invention is an improved flashing for use across the angles between roofs and fire walls of chimneys, or for application in 15 other points where flashings are commonly used or may be used to advantage.

The object of the invention is to provide an inexpensive flashing which may be easily applied, yet one which will be highly efficient and durable and will effectively exclude moisture and wind at all times, provision being made whereby the flashing may readily expand and contract with the parts to which it is secured, under changes in temperature.

With this general object in view, the invention resides in certain novel features of construction and in unique arrangements of parts to be hereinafter fully described and 30 claimed, the descriptive matter being supplemented by the accompanying drawing which constitutes a part of this application and in which:

Figure 1 is a sectional perspective of a 35 portion of a roof and fire wall showing the application of the invention thereto, and, Fig. 2 is a true vertical section of the parts shown in Fig. 1.

In these drawings, the numeral 1 designates a roof, while 2 refers to a fire wall rising beyond the edge of said roof, it being 40 across the angle between these parts that the improved flashing 3 is applied, the roof proper being covered with any preferred 45 roofing material 4.

The improved flashing 3 is formed by extending one or more intersticed sheets of material such as that shown at 5 across the angle between the wall 2 and roof 1, and 50 by applying a covering 6 of non-drying weather-proof cement to the upper surface

of the aforesaid material 5. The material 5 may be of wire fabric as shown in the drawing, metal lath or any other suitable metal having therein interstices into which the cement 6 may be worked to hold said cement in operative position. Similarly, this cement may be of any desirable composition, but its ingredients preferably are non-drying oils, asphalt, pitch or varnish, 60 and asbestos fiber. It will be understood, however, that I do not wish to be limited to these specific ingredients since as above stated any appropriate cement may be used. The material 5 will be preferably secured 65 along its lower edge to the roof 1 by nails or staples 7, while the upper edge of such material will usually be received in a horizontal groove 8 formed in the wall 2. Here again, however, I do not wish to be limited 70 to this exact manner of anchoring the part in question. Regardless of the manner in which it is anchored, however, the covering 6 will extend beyond its edges onto the wall and roof to which said covering is adhered 75 by its viscous qualities. If the groove 8 be provided, a sufficient quantity of the covering 6 will be worked into said groove to effectively exclude moisture therefrom as will be readily understood.

By constructing the improved flashing in the manner shown and described, it will be obvious that it will be inexpensive yet efficient and durable.

It will be understood that non-drying 85 cement is essential, since it allows readily for expansion and contraction of the flashing with the roof and wall, as the latter parts vary in temperature.

I have shown and described the flashing 90 3 as applied across the angle between a roof and a fire-wall, but I wish it understood that it may be used for preventing the entrance of moisture around a chimney, or may be employed at any other point where 95 a flashing is needed.

I claim:

A flashed joint between a roof and a wall having a groove above said roof, comprising a strip of openwork fabric secured at 100 or near one edge to the roof and having its other edge inserted in the groove, said strip

being of such rigidity as to maintain said edge in said groove, and a plastic layer worked into said fabric and closing the groove, said layer tapering off above the groove and also tapering out over the roof and beyond the edge of the strip secured thereto.

In testimony whereof I have hereunto set my hand in presence of two subscribing witnesses.

HOMER H. DUNLAP.

Witnesses:

H. NEAPH,
H. W. WYLIE.
